[57] **CLAIM**

The ornamental design for a wing, as shown and described.

DESCRIPTION

FIG. 1 is a perspective view of a wing embodying our design;

FIG. 2 is a top plan view thereof;

FIG. 3 is a left side elevational view thereof, the right side being a mirror image of that shown;

FIG. 4 is a rear elevational view thereof; and,

FIG. 5 is a front elevational view thereof.

The broken-line disclosure of a portion of a surface and latch in the views are for illustrative purposes only and forms no part of the claimed design.
